IRONING BOARD

Filed June 8, 1929

UNITED STATES PATENT OFFICE

WALLACE L. KULLBERG, OF MINNEAPOLIS, MINNESOTA

IRONING BOARD

Application filed June 8, 1929. Serial No. 369,278.

This invention relates to an ironing board and particularly to such a board adapted to be collapsed and stored in a small space, particularly a chamber beneath a table. As is well known, many modern apartments are quite small and it is desired to use the space to the greatest advantage. An ironing board which may be ordinarily disposed beneath the dinet table or kitchen table is therefore a great convenience.

It is an object of this invention, therefore, to provide a simple and efficient structure of ironing board which may readily be collapsed and stored in a small space such as a chamber beneath a table and which may be easily and quickly withdrawn and arranged in operative position.

It is a further object of the invention to provide such a board having a top member, a leg slidably connected thereto, a link or brace extending from said leg to one end of the board, and supporting members connected to said link or brace and arranged to cooperate with the sides of the recess in the table or other member to slide therein.

It is more specifically an object of the invention to provide an ironing board structure comprising a table having a chamber beneath the top thereof with side walls, said walls having slots therein with a pocket at the end thereof, a pair of bars having means projecting therefrom movable in said slots and adapted to seat in said pockets, a member pivotally secured to the outer ends of said bars and pivotally connected at one end to an ironing board top, said member being secured at its other and lower end adjacent the end to a supporting leg for said top slidably connected to said top whereby said structure may be collapsed and stored under the table top or readily moved outward and arranged in operative position.

These and other objects and advantages of the invention will be fully set forth in the following description made in connection with the accompanying drawings, in which like reference characters refer to similar parts throughout the several views, and in which:

Fig. 1 is a view in side elevation of the

table and ironing board structure, the same being shown in operative position and being shown in collapsed position ready to be moved under said table in dotted lines;

Fig. 2 is a top plan view of Fig. 1;

55

Fig. 3 is a view taken on line 3—3 of Fig. 2 as indicated by the arrows showing a portion of the board in operative position;

Fig. 4 is a vertical section taken on line 4—4 of Fig. 1 as indicated by the arrows;

60

Fig. 5 is a vertical section taken substantially on line 5—5 of Fig. 4 as indicated by the arrows;

Fig. 6 is a vertical section taken on line 6—6 of Fig. 2 as indicated by the arrows;

65

Fig. 7 is a vertical section taken on line 7—7 of Fig. 3 as indicated by the arrows, and

Fig. 8 is a vertical section taken on line 8—8 of Fig. 3 as indicated by the arrows.

70

Referring to the drawings, a table 10 is shown having a casing therebelow with side members or walls 11, a bottom member 12 and a rear end wall 13. Table 10 and casing 11 are supported at one end of a strip or cleat 14 secured to the wall 15 of the room, said wall being illustrated as having a base board 16 and molding 17 at the bottom thereof adjacent the floor 18. Walls 11 have legs 19 extending vertically at each side thereof adjacent their outer ends which extend to and support the top of the table. Small brackets or braces 20 having curved outer surfaces are secured to the walls 11 and beneath the top of the table 10 which over-hangs walls 11. The casing having side walls 11 and bottom 12 has an open front end adapted to be closed by a door 21 connected by a hinge 22 to bottom member 12, said door having a small knob or handle 21a at its outer side. The walls 11 at their inner sides are provided with slots 11a, which slots at their rear portions extend parallel to the bottom edge of walls 11 and bottom 12 but at the outer ends incline upwardly as shown in Fig. 3, said slots terminating a short distance from the outer ends of walls 11 and having a downwardly extending end portion forming a pocket 11b. A pair of bars 3 are provided connected at their bottom side for a

75

85

90

95

100

portion of their length by a plate or board 24. Bars 23 have respectively secured thereto spaced outwardly extending pins 25 and 25a which project into and are adapted to 5 slide in the slots 11a. Bars 23 at their inner sides are provided with slots 23a, said slots being disposed adjacent the tops of said bars and having downwardly curved outer ends forming pockets 23b. A pair of bars 26 are 10 also provided connected to be disposed in parallel relation and having extending therebetween a rod 27. This rod projects at the outer sides of said bars and has its ends disposed in and adapted to slide in the slots 15 23a. The bars 26 are respectively connected at their upper ends by hinges 28 to the under side of a top ironing board 29, the ends of bars 26 being beveled or cut at an angle to fit against the bottom of board 29. At their 20 other ends bars 26 are connected by a rod 30 extending therebetween and forming a pivot for the leg members 31 through which it passes, said leg members being connected adjacent their upper ends by a board or 25 plate 32. Plate 32 has a screw-eye 33 secured thereto and projecting upwardly therefrom at an angle and a rod 34 extends through said eye 33, said rod being secured at its ends in board 29 and being disposed intermediate its ends in a groove or recess 29a formed in the bottom of board 29 for a portion of its length. Board 29 has a strip 35 secured to its under side and extending transversely thereof adjacent its outer end and over-lying the outer portion of slot 29a. Strip 35 has a lip or tongue 35a at its lower end projecting toward table 10 and at its upper end projecting toward table 10. When so collapsed, the upper ends of leg members 31 and board 32 move rearwardly or toward table 10 by eyelet 33 40 is in operative position. Board 29 has another strip 36 secured to its under side and parts, without departing from the scope of extending transversely thereof adjacent the other end of slot 29a and over-lying a portion of the said slot. 45 In operation the ironing board may be collapsed and moved into the casing beneath table 10. When so collapsed, the upper ends of leg members 31 and board 32 move rearwardly or toward table 10 by eyelet 33 50 sliding on rod 34 as illustrated in Fig. 5. Brace members 26 then fold up beneath and pivotally connected to its bottom side of board 29 at each side of legs 31 as shown in dotted lines in Fig. 1. The board structure connected to said leg adjacent its lower end and can then be moved under the table by pushing on the same, bars 23 being lifted slightly to said board beneath the other end thereof, to lift pins 25 out of pockets 11b, after which 55 and bars pivoted intermediate the ends of bars 23 will slide rearwardly, pins 25 and 25a said bars and slidably connected with the moving in slots 11a. When said bars are moved under the table the board structure 60 will be lifted slightly to move rod 27 out of pocket 23b and parts 26, 29 and 31 can then be moved completely under the table, the ends of rod 27 sliding in slots 23a. Door 21 65 can then be closed and the ironing board structure is entirely disposed in the casing in said slots, said slots having portions re- 70 75 80 85 90 95 100 105 110 115 120 125 130

beneath the table. When the board is to be placed in operative position, door 21 will be opened and the end of board 29 pulled outwardly. Pins 25 will slide outwardly in slots 11a until they reach the end of said slots when they will drop into pockets 11b and will be prevented from endwise movement backward in slots 11a. Board 29 is pulled forward outwardly, the ends of pin 27 moving in slots 23a until it reaches the end of said slot when its drops into pockets 23b, so that bars 26 cannot move toward the table. Legs 31 are now swung about pivot rod 30, eyelet 33 traveling on rod 34, and the upper end of legs 31 and board 32 are brought against the cleat 35, tongue 35a and the slot in board 32 engaging to bring said legs to a vertical position. When in this position the top 29 is raised some distance above the top of table 10 and the board 32 occupies a firm position as shown in Fig. 1. There is no tendency of the board to collapse or to move toward the table on account of the structure is thus maintained in extended and firm position.

From the above description it is seen that applicant has provided a very simple and efficient structure of ironing board and one which can be quickly and easily collapsed and moved into a recess such as that formed in the bottom of board 29 for a portion of its length. The parts of the device are quite few and simple and the structure is easily made and assembled. The device has been fully demonstrated in actual practice and found to be very successful and efficient. It will, of course, be understood that various changes may be made in the form, design and proportions and arrangement of the parts, without departing from the scope of the invention, which, generally, consists in a device capable of carrying out the objects above set forth, in the claims closed and defined in the appended claims. What is claimed is:

1. An ironing board structure having in combination with a member having a recessed slidingly on rod 34 as illustrated in Fig. 5, with walls, a board having a leg slidingly connected to said leg adjacent its lower end and hingedly connected at their other ends to said board beneath the other end thereof, and bars pivotally connected to its bottom side of board 29 at each side of legs 31 as shown in dotted lines in Fig. 1. The board structure connected to said leg adjacent its lower end and can then be moved under the table by pushing on the same, bars 23 being lifted slightly to said board beneath the other end thereof, to lift pins 25 out of pockets 11b, after which and bars pivoted intermediate the ends of bars 23 will slide rearwardly, pins 25 and 25a said bars and slidably connected with the moving in slots 11a. When said bars are moved under the table the board structure 2. An ironing board structure having in combination with a table having a recess therein with side walls, said walls having longitudinal slots therein, a member moveable in said recess having means slidably connected to said table beneath the other end thereof, and bars pivotally connected to its bottom side of board 29 at each side of legs 31 as shown in dotted lines in Fig. 1. The board structure connected to said leg adjacent its lower end and can then be moved under the table by pushing on the same, bars 23 being lifted slightly to move rod 27 out of pocket 23b and parts 26, 29 and 31 can then be moved completely under the table, the ends of rod 27 sliding in slots 23a. Door 21 can then be closed and the ironing board structure is entirely disposed in the casing in said slots, said slots having portions re-

- ceiving said means to prevent movement of said member into said recess when said member is moved to extend out of said recess, a member comprising a pair of bars pivotally connected to said first mentioned member, a board pivotally connected at one end to one end of said last mentioned member, a leg member pivotally connected to the other end of said last mentioned member and pivotally connected at one end to said board and means for preventing inward movement of said second mentioned member toward said recess when said board is in operative position.
3. The structure set forth in claim 2, said second mentioned member being slidably connected to said first mentioned member and said leg member being slidably connected to said board.
4. An ironing board structure having in combination with a table having a recess therein, a member slidably connected to said table and movable in and out of said recess, a member slidably and pivotally connected to said first mentioned member and adapted to swing into alignment therewith, a board pivoted adjacent one end of said last mentioned member, a leg pivoted adjacent the other end of said last mentioned member, and pivotally connected adjacent one end to said board, means preventing inward movement of said first mentioned member when withdrawn from said recess and means preventing inward movement of said second mentioned member relative to said first mentioned member when said board is in operative position.
5. An ironing board structure having in combination with a table having a recess therein, a member slidably connected to said table and movable in and out of said recess, a member pivotally connected to said first mentioned member and adapted to swing into alignment therewith, a board pivoted adjacent one end of said last mentioned member, a leg pivotally and slidably connected to said board and of a length greater than the height of said table, and an operative connection between said leg and said second member, whereby to support said board in position above the level of said table.
6. The structure set forth in claim 5, a stop engaged by said leg when said table is in operative position and means for preventing said first mentioned member from moving into said recess when said board is in operative position.
7. An ironing board structure having in combination with a table having a recess therein, a member slidably connected to said table and movable in and out of said recess, a member slidably and pivotally connected to said first mentioned member and adapted to swing into alignment therewith, a board pivoted adjacent one end of said last mentioned member, supporting means connected to the other end of said board, and an operative connection between said supporting means and said second member, whereby to support said board in operative position at a greater height than said table.
8. An ironing board structure having in combination with a table having a recess therein, a member movable into and out of said recess, said member comprising parallel bars having longitudinal slots therein, a second member comprising parallel bars having means thereon intermediate their ends respectively disposed in and slidable in said slots, said slots having recesses respectively at their outer ends for receiving said means, a board pivotally connected to one end of said second member, a leg pivotally connected to the other end of said second member and connected to said board, and being longer than the height of said table for supporting said board in operative position above the level of said table.
9. An ironing board structure having in combination with a table having a recess therein, a member movable into and out of said recess, means for limiting the movement of said member and preventing movement into said recess when withdrawn to its limit therefrom, a second member slidably and pivotally connected intermediate its ends to said first mentioned member, a board pivoted adjacent one end of said second mentioned member, a leg structure pivoted at the other end of said second member, said leg being pivotally connected to the board and of greater length than the height of said table whereby said board may be supported in operative position above the level of said table.
10. An ironing board structure having in combination with a table having a recess beneath the top thereof means pivotally and slidably connected to said table within said recess and arranged to be disposed within and withdrawn from said recess, a member pivotally connected to said means, a board connected adjacent one end to said member so as to fold close to and substantially parallel to said member and a supporting means pivotally connected adjacent the other end of said member of such length as to cooperate with said member to support said board with its top disposed in a plane higher than the top of said table.
11. An ironing board structure having in combination with a table having a recess therein, a member slidably connected to said table and movable in and out of said recess, means slidably and pivotally connected to said member and adapted to fold into close relation therewith, an ironing board connected at one end to said means so as to

folded into substantially parallel relation therewith, a leg member of greater length than the height of said table, and an operative connection between said means and 5 leg member.

In testimony whereof I affix my signature.

WALLACE L. KULLBERG.
